METHOD AND MEANS FOR MOLDING EDGE PORTIONS OF MATERIAL

Frank Paparella, Needham, Mass.

Application July 3, 1933, Serial No. 678,763
In Canada January 21, 1933

22 Claims. (Cl. 223—57)

This invention relates to garment pressing methods and devices and particularly to a process and apparatus for molding and shaping edge portions of multi-ply material whereby to reproduce in the material, the pattern of the garment.

In the manufacture of clothing considerable difficulty has been experienced in shaping edge portions of material and this problem has been most troublesome in the formation of the lapel and collar portions of coats and overcoats. Heretofore it has apparently been impossible, as a practical matter, to shape lapels and collars to conform exactly to the outline of the pattern and this problem has been a matter of concern to clothing manufacturers as it is to the relatively minute details of the shape of those portions of the garment that the skill of the designer is chiefly directed and to which the style of the garment is largely attributable. Deviations from the carefully considered details of the pattern have commonly appeared as a distortion in the edge contour of the material particularly at the point of the lapel, a substantial departure from the pattern in the angle of the notch separating the lapel and collar and a discrepancy involved in the manual operation of folding or turning back the exposed surface of the lapel and collar which heretofore has been an operation involving considerable skill.

I have found that the above-noted difficulties can be obviated and a lapel and collar produced which conforms exactly to the edge contour of the pattern by initially steaming the material to render it plastic and thereafter externally confining and crowding the edge of the material to the shape of the pattern whereby to produce a billowing or undulating of the surplus material so confined. I then apply pressure in a direction normal to the surfaces of the material whereby simultaneously to press the surfaces and to mold the edge portions by resisting the resultant extrusion or lateral spreading of the material at the edges caused partly by the flattening of the billows. The effectiveness of this edge molding operation is enhanced by a further step in my method wherein, while maintaining or even increasing the pressure between the edge of the material and its confining body, I pass that body transversely of the edge of the material to iron the same.

The lapel and collar of a finished garment which is ready to wear comprises the outer and inner surfaces of material which are bounded at one edge by the molded seam referred to above and at the other edge by the crease or fold on

which the material is turned back to form the exposed lapel and collar surface. My method secures the proper shaping of the exposed surface in its entirety by molding the seamed edge, pressing the outer and inner surfaces and simultaneously initiating the fold in the proper position relative to the shaped edge, thereby mechanically defining the lapel and collar in the exact shape desired. The fold-initiating step I have accomplished by forming an elongated impression in the material while its edge portion is being molded so that, as the edge is brought to the desired contour and the surfaces are being pressed, the position of the fold in relation to the shaped edge is mechanically predetermined.

Any suitable apparatus may be employed for carrying out my novel process but I have devised novel apparatus which I have found to be particularly well adapted for that purpose and which I have made the subject matter of my prior co-pending application, filed October 13, 1932, Serial Number 637,622, of which the present application is a continuation in part.

It is the object of my present invention not only to provide a method of molding multi-ply material which is adapted for use to mold coats, overcoats and the like but also to improve on the apparatus disclosed in my above-noted application. This latter object I have secured by providing novel upper and lower presser members which can be incorporated in an ordinary pressing machine and which, as will appear, are so adapted for use with my novel mold as to improve in the operation of the mold over that obtained by the use of my mold with common forms of pressing machines now on the market.

In the drawings:—

Fig. 1 is a perspective view of the forepart and facing of a garment shown inside out during the process of manufacture;

Fig. 2 is a perspective view of the garment portions of Fig. 1 shown after the turning operation;

Fig. 3 shows a coat completely made and ready for my novel lapel and collar molding process;

Fig. 4 is a vertical sectional view taken on the line 4—4 of Fig. 1;

Fig. 5 is a plan view of a completely made lapel and collar, shown disposed adjacent my novel mold which is formed in the shape of the pattern, to indicate the departure of the lapel and collar portions from the desired edge contour;

Fig. 6 is a perspective view of a lapel and collar portion of a garment during an initial stage in the molding process;

Fig. 7 is a plan view of the finished lapel and collar portion after molding, showing the position of the fold defining impression;

Fig. 8 is a sectional elevation view on the line 5 8—8 of Fig. 6;

Fig. 9 is a view similar to Fig. 8 with the parts shown at a later stage in the method;

Fig. 10 is a perspective view of my novel supporting table and upper presser member adapted 10 for use with my molds;

Fig. 11 is a plan view of the supporting table;

Fig. 12 is an elevation view, partly broken away, of the parts shown in Fig. 11;

Fig. 13 is a sectional elevation view taken on 15 the line 13—13 of Fig. 11 but showing the upper presser member closed on the material adjacent the mold;

Fig. 14 is an enlarged sectional elevation view of a detail of Fig. 13, and

20 Fig. 15 is an enlarged sectional elevation view taken on the line 15—15 of Fig. 11.

Referring to the drawings and particularly to Fig. 1, the lapel of a garment is usually made of two plies of material, the forepart 1 extending 25 from the shaped edge 2 to the edge 3 where the forepart joins the back of the garment in a seam, and a second ply 4 called the facing and extending from the edge 5 to the edge 6 where it is joined to the lining 7. At the stage of manufacture illustrated in Fig. 1, the lapel is inside-out, the canvas 10, usually padded, has been caught to the inner surface (now exposed) of the forepart 1 by stitching 11 which catches but does not pass completely through the forepart (Fig. 30 4); the forepart and facing have been superimposed and cut to form the edges 2 and 5 and the edge seam 12 has been stitched through the forepart 1, facing 4 and a piece of tape 14 commonly provided to prevent stretching of the material at the edge. As illustrated in Fig. 4, the canvas 10 terminates short of the seam 12 and the tape 14 is caught to the canvas by a row 40 of stitching 15. The collar has not yet been attached and will later be joined to the lapel along the rough edges indicated at 16.

50 I am assuming that the lapel is being made of heavy overcoat material and that the designer has chosen a sharply pointed lapel as best suited for the style of garment being made, as is common in double breasted overcoats, and I have 55 illustrated the sharp point desired at 42A in Fig. 7 which shows the finished lapel after having been molded in accordance with my invention. The line of stitching 12 forming the seam is made to conform as nearly as possible to the desired shape and for that purpose is brought as 60 nearly as possible to the sharp point illustrated at 20.

60 The forepart and facing, after being joined at the seam 12, are turned right side out as shown in Fig. 2, and in this turning operation the operative tries to shape the lapel to make it conform as nearly as possible to the pattern. To 65 do this the cloth must be manually forced back from the seam 12 to bring the seam as nearly as possible to the outer edge of the lapel because, it will be remembered, the seam is made to conform as closely as possible to the outline of 70 the pattern. The material is usually basted progressively as the edge is worked as indicated at 21 to hold the material as it is being manipulated and prevent the seam from rolling back as indicated at the unbasted portion 27. To force out 75 the point of the lapel a sharply pointed imple-

ment is inserted and the cloth brought as nearly as possible to the sharp point desired.

It is obvious that this turning operation cannot produce a lapel which conforms exactly to the shape of the pattern regardless of how carefully it is performed. The manual pulling of the bulky material causes it to stretch more at some portions than others to produce a wavy contour and it is exceedingly difficult to force the material back from the seam evenly at all portions. The point of the lapel will almost inevitably be bulging and rounded rather than sharply pointed as desired due to the practical inability of the operative to completely reverse the pointed seam stitching. Even with the seam cloth 10 partly cut away at the point, the tip will be bulky and under the common pressing operations as practiced heretofore the flattening of the point causes the excess seam cloth to extrude or flatten out and thereby cause the edge contour of 20 the tip to depart still further from the desired sharp point. The construction of a lapel and the precautions taken in an effort to preserve the shape of the pattern are not described in detail herein as the difficulties involved are well-known 25 to clothing manufacturers and my manner of solving the problem will be fully appreciated by them.

After the turning operation the lapel is frequently given a marginal line of stitching as 30 shown at 22 (Fig. 3) to give the lapel a more dressy appearance and this stitching passes completely through the canvas-padded forepart and facing, joining those two plies internally. Thereafter the coat is finished, the collar being joined 35 by a seam 23 and the buttonhole 24 being formed by cutting through both plies of material and lining the hole with a marginal line of stitching.

After the coat has been completely made, as indicated in Fig. 3, it is ready for the pressing 40 operations when my invention comes into use.

The specific manner in which the lapel of a completely manufactured coat usually departs from the design of the pattern may well be illustrated by a comparison of the lapel with the 45 mold of my apparatus which is shaped in exact conformity with the pattern. Thus I have illustrated in Fig. 5 a portion of a coat having a lapel 30 and collar 31 resting adjacent a pressing mold 32. The mold 32 has a molding wall 50 edge 33 which, as illustrated more clearly in Fig. 6, comprises a portion 33A shaped to conform to the front edge of the lapel of the pattern and a molding edge 33B conforming to the initial edge portion of the collar and separated from the 55 portion 33A by an angular molding portion 33C which is adapted to receive the tip of the lapel and, in accordance with the design of the pattern illustrated, is brought to a sharp point 33D. The molding edge 33 also includes the side surfaces of a projecting strip 33E adapted to fit nicely into the notch separating the collar and lapel portions of the pattern. Comparing the contour of the entire molding edge 33 which, as stated, exactly conforms to the pattern, with the 60 lapel and collar portions 30 and 31 of the garment illustrated in Fig. 5, it will be noted that the long edge 48 of the lapel is wavy and not smoothly curved in conformity with the pattern. Probably the discrepancies illustrated have arisen 65 through unequal turning back of the material adjacent the edge seam or possibly the material has been stretched more in some places than in others. In sewing the buttonhole 41 the operative usually tensions the cloth considerably at cer- 75

tain portions of the edge and the material is also contracted somewhat as a result of the large number of marginal stitches lining the button-hole. The tip 42 of the lapel will almost invariably be considerably rounded and otherwise misshapen in comparison with the sharp point of the pattern. Furthermore, the degree of inclination of the tip of the lapel in comparison with the position of the collar will very frequently be at variance with the design of the pattern as indicated by the arrow. It will be noted that the edge 49 of the collar not only does not conform to the curvature of the collar molding edge 33B but is spaced considerably therefrom and it will be found that if the lapel were, for the moment, freed from the molding edge 33A and the edge 49 of the collar were moved closely against the wall 33B of the mold, the angle of inclination of the tip would involve a still greater departure from the pattern than that illustrated.

To remedy the above-noted discrepancies and to completely re-shape and mold the material into substantially exact conformity with the pattern by the use of pressures applied only externally to the surface of the material my novel method provides for the initial step of thoroughly steaming the material. As is known in the garment pressing art, the effect of steam on garment material is to render it somewhat plastic and easily moldable to the form desired. While the material is in this semi-plastic condition I next manually distribute and crowd the material against and within a confining wall which restricts the edge of the material to the shape desired. Thus, as illustrated in Fig. 6, where my method is being employed to shape the lapel of a garment, I have found that the first step of manipulating the material to bring its edge in snug engagement with the molding wall should preferably be to draw the tip 42 of the lapel well into the corner 33D of the mold and this may be easily accomplished by the use of a thread 50 which has been caught through the tip end 42 of the lapel prior to the steaming step. Then, after the cloth has been steamed, the thread may be tensioned to draw the tip 42 into the sharp corner 33D and the thread should be secured to maintain the tip in this position. The step of manipulating the material to confine it to the shape desired also includes manually moving the material to bring the edge 49 of the lapel closely contiguous to the molding edge 33A of the mold throughout its entire length and the edge 49 of the collar should similarly be moved firmly against the edge 33B of the mold.

When the material has been so steamed and manipulated to position it closely adjacent the molding edge, it will be found that there is a surplus of material confined adjacent the molding edge which will cause a billowing or undulating of the material, as illustrated at 60 in Fig. 6. Thus it will be apparent that when the tip 42 of the lapel was crowded into the sharp angular recess 33D of the mold, an excessive amount of material was disposed throughout the angular portion 33C of the mold, which surplus is illustrated at 61 in Fig. 8. Similarly throughout the entire area of material to be molded there will be a surplus of material which because of the action of the steam, will undulate as indicated.

The next step in my method comprises applying pressure to the upper and lower surfaces of the material to flatten out the billows and initiate a molding pressure between the edge of the mold and the edge of the material through the result-

ing lateral displacement or extrusion of the material at the edges. Thus, as illustrated in Fig. 9, the material has been supported on a suitable flat surface 78 and a suitable pressure applying medium 74 is brought into engagement with the entire top surface of the material, whereby pressure is applied to both surfaces of the material. As a result of this pressure on the surplus material illustrated at 61 the material will flatten out, as shown at 61A, thereby exerting lateral pressure between the side edges 40 and 45 of the material and the walls 33C of the confining body. If the material be held in this flattened condition for a brief interval during which the pressures are maintained between the sides of the material and the molding walls, it will be found that the material will redistribute itself and will permanently set in the shape imparted to it by its confining walls.

I have found that the effectiveness of my novel method can be further enhanced by an additional ironing step wherein simultaneously with the application of pressure between the edge of the material and the molding wall, the wall is passed transversely of the edge. Thus as indicated by 25 a comparison of Figs. 8 and 9, the confining walls 23 were lowered during the period when the material was being compressed between the upper and lower members 71 and 70. This additional ironing step aids in more sharply defining the 30 edges.

As stated above, the lapel and collar portions will not be reproduced in the garment in exact conformity with the pattern even though the edges be perfectly shaped, unless the lapel and 35 collar is turned back to expose an area which not only conforms exactly with the width of the pattern, but which also reproduces exactly the lapel of the design in the position of the edge of the lapel and collar relative to the body portion of 40 the coat. To insure mechanically that the folded-back portions accord with the design and to eliminate the necessity for a skillful and careful manual operation in this respect, I provide that simultaneously with the molding of the edge and 45 during the time when the material is plastic under the influence of the steaming step, the garment is impressed with an elongated indentation disposed at a predetermined distance from the molded edge whereby to render the lapel and 50 collar easily foldable along the grooved portions and to initiate the fold at the desired position. Thus, as indicated in Fig. 7, an impression 80 is made in the garment at a predetermined distance A from the inner extremity of the notch 55 separating the lapel and collar and at the proper angle relative to the edge 40A of the lapel to provide a fold in the desired position.

With a garment molded in accordance with my novel method it will be found that the edges 60 40A and 49A of the lapel and collar respectively have been brought in substantially exact conformity to the pattern and will retain their shape when the material is removed from the mold. Furthermore the point 42A of the lapel has been 65 transformed from the rounded and comparatively unsightly tip 42 to a sharp point as desired. If the design of the pattern had provided a rounded tip rather than the sharply pointed one 70 illustrated, the proper curvature would be reproduced in the garment. Furthermore the angle of inclination of the tip indicated by the arrow, has been reproduced in the garment. When the garment is removed it will be found further that 75 the lapel and collar will fold back almost of their

own accord along the line 80 whereby both lapel and collar portions of the same garment will not only be exactly alike but will be in the shape of the pattern.

5 As stated above, it is one of the objects of my invention to improve on the apparatus disclosed in my prior application above noted, which I have found best adapted for performing my novel method and this object I have secured through 10 the provision of novel upper and lower presser members which are particularly adapted for use with my novel molds. The advantages secured by the provision of such members will appear as the description proceeds and will be pointed out 15 in detail hereinafter.

Referring now to Figs. 10-15 inclusive, my pressing machine comprises in general a lower presser member or table 100, suitably mounted, which is adapted to support and removably position one or a plurality of pressing molds in operative position. As indicated in the drawings, the machine is designed for the simultaneous pressing of a right and left hand lapel and collar portion of two coats of the same style. To that end 20 the table 100 is provided with a pair of flat supporting surfaces 101, the left hand one of which is shown in Fig. 10,—the right hand surface 101 being concealed by the mold assembly 102 which is shown in pressing position. A detailed description of the pressing or mold assembly 102 need not be set forth herein as reference for that purpose may be had to my prior application above noted, but in general the assembly comprises two members, namely a mold 103 whose edge 104 is 30 shaped to conform to the desired contour of the edge portions of the garment to be pressed, and a cloth supporting piece 105 having edge portions shaped in the pattern of the garment and adapted to abut the edge 104 of the mold 103. The mold 40 103 and the cloth supporting piece 105 are secured together as a unit by means 106 (Fig. 11) which permits a limited relative movement between them in a direction transverse of their mating edges whereby the mold and cloth supporting member may be disposed either in the same plane or with the mold stepped up from the cloth supporting piece 105, as shown in Fig. 10, to expose the molding edge wall 104.

The table 100 is provided at its periphery with 50 a pair of ledges 110 which may suitably comprise plates disposed on the outer margins of the surfaces 101 and secured thereto by means of suitable screws 111. The purpose of the ledge 110 is to assist in positioning the mold assembly in 55 pressing position and for that purpose the edge 112 of both ledges 110 should be shaped to abut firmly the corresponding edge of the cloth supporting piece 105. As will appear, the ledge 110 performs a further function, namely, that of forming a continuation of the upper exposed cloth supporting surface of the member 105 and to that end the ledge or plate 110 should be of a thickness which is substantially the same as the thickness 60 of the supporting piece 105 so that the upper exposed surface of the supporting piece and ledge will lie in the same plane.

To yieldingly support a pair of pressing molds 103 with their molding wall edges 104 exposed in an amount exceeding somewhat the thickness of the material to be molded, the table 100 is provided with three spring supported platforms, two of which are disposed in the back of the machine, as indicated at 120 and 121, and the third 70 of which is disposed in the front of the machine 75

as shown at 122. These platforms are substantially alike in construction and as indicated in Fig. 12 the platforms are yieldingly supported by springs 123 which abut the under surface of the platforms and are seated on suitable nubs projecting from flanges 124 integral with or secured to the table 100. To guide the platforms in their vertical reciprocation, the flanges 124 are each provided with a pair of bosses 130 and 131 which are drilled to receive slidably a pair of plungers 10 132 and 133 depending from the under surfaces of the platforms. The lower extremities of the plungers 132 and 133 may be screw threaded to receive the nuts 135 which limit the upward travel of the platform.

15 The only substantial difference in construction between the front platform 122 and the rear platforms 120 and 121, is that the front platform is designed to support the forward extremities of two pressing molds whereas the rear platforms each support only the rear portion of a single adjacent mold. In each instance, however, the platform is provided with a horizontal supporting surface 140 which is yieldingly held elevated above the plane of the adjacent surface 25 101 and is formed at its outer margin with a vertical wall 141. Secured to the top of the wall 141 is a plate 142 which projects somewhat over the surface 140 to form therewith a recess adapted to receive a flange 143 (Fig. 11) which is cast integrally with the mold 103. The plate 142 provided for the front platform 122 is somewhat more extensive than the corresponding plates for the rear platforms whereby to receive and removably secure the front flanges 144 of both 30 35 the right and left hand molds as indicated in Fig. 11.

As additional means for positioning the mold assembly, the surface 101 of the table is provided with a suitable number of dowels 145 which, as 40 will appear, are received in corresponding recesses in the cloth supporting piece 105.

The novel upper presser member of my machine, indicated generally at 150, should preferably be shaped in the general outline of the 45 table 100 and is mounted adjacent the rear of the table by suitable hinge mechanism 156 of the usual type common to pressing machines. The presser member 150 is provided with a pair of plane pressing surfaces 151 to correspond with 50 the supporting surfaces 101 of the table. Any suitable means may be provided for heating either the upper presser member 151 or the table 100, or both, and for providing for the passage of steam and drying air through the material. Such apparatus forms no part of my invention but I have indicated diagrammatically in Fig. 13 a suitable heat coil 152 communicating by piping such as at 153 (Fig. 10) with a supply of steam indicated at 154. The presser member 150 may be recessed at 160 to provide a steam chamber communicating through a number of ducts or perforations 161 with the pressing surfaces 151 to 60 conduct steam to the material being pressed.

65 Pressing apparatus of this type may also include means for supplying moistening steam to the garment from the bottom and should also be provided with means for sucking air through the material to dry the same. For this purpose 70 the table 100 is provided in each surface 101 with an orifice 161 which communicates by suitable piping 162 (Fig. 13) with a steam supply and also with a second orifice 163 which communicates by means of the piping 164 with any 75

form of suction apparatus well known in the art. It will be noted that the cloth supporting piece 105 is perforated throughout its cloth supporting area as indicated at 170 and these perforations 5 communicate from the exposed surface of the piece 105 to a chamber 171 which is formed by hollowing out the under surface of the piece 105. As described in my copending application, the cloth supporting surface of the supporting piece 10 is strengthened and reinforced by a plurality of nubs 172 formed within the chamber and on the top surface thereof. These nubs 172 project downwardly to rest on the surface 101 of the table and afford support against the high pressures exerted by the upper presser member. By 15 the provision of the chamber 171, which is continuous throughout the under surface of the supporting piece except for the area occupied by the nubs, I am able to secure distribution of steam or vacuum throughout the entire surface of the supporting piece and yet require but a single point of supply in the surface of the table as indicated at 161 or 163. The dowels 145, above referred to, may be received by recesses drilled 20 in suitable nubs which are positioned to fit over the dowels as shown in Fig. 15, or if desired, the dowels may be of sufficient height to project into corresponding recesses in the upper surface of the chamber 171.

30 As described above in connection with the method aspect of my invention, it is most desirable to be able to impress the material with an elongated indentation whereby to initiate a fold in the material at the desired position. For 35 this purpose the ledges 110 are each provided with a rib 180 which may be cast in the upper surface of the ledge 110 or which may comprise separate elements suitably secured to the surface of the ledge. The steam and drying air should 40 have access to that portion of the material which is to be grooved and for that purpose the ledge or plate 110 is chambered in its under surface as indicated at 182 and provided with suitable strengthening nubs. The chambers 171 and 182 45 communicate with each other and the plate 110 is provided with perforations 183 communicating with the chamber 182.

I have found that a more effective operation of 50 impressing the cloth with an indentation can be obtained by providing, in each of the faces 151 of the upper presser member, a groove 181 which is properly positioned in the face 151 to receive its rib 180 when the machine is closed. The grooves 181 should preferably be cut in the shape indicated in Fig. 14 and be lined with cloth padding 55 281 which will provide a yielding cushion to cooperate with the ribs 180 and will adapt the rib and groove for efficient operation with all the various thicknesses of material with which my 60 machine is designed for use.

To secure the material in pressing position with the edge of the material to be molded closely abutting against the molding wall 104 of the mold, each of the molds is provided with two 65 spring pressed clips 190 and 191 secured to the flanges 143 and 144 respectively of the mold. To draw the point of the lapel firmly into the corresponding notch of the molding edge 104, the 70 above mentioned piece of thread which is caught through the point of the lapel, is guided through a groove 192 formed in the mold and to spring pressed thread engaging means 193 secured to the rear portions of each of the platforms 120 75 and 121. The details of the spring clips and

thread engaging means are set forth in my prior application.

In conclusion it should be stated that the description of my novel pressing machine has been confined, with the exceptions noted, to the novel features of construction which form the subject matter of my invention and it is to be understood that my device is provided with all of the usual appurtenances which are common to machines of this type. Thus the apparatus shown for conducting steam and drying air to and through the material will be constructed as has been found most suitable in the art and will include the usual system of treadles for operating the necessary valves. The device should also include the usual treadles and associated mechanisms for producing varying degrees of pressure between the upper presser member 150 and the material to be pressed and such mechanism should be adapted to lock the member 150 into firm engagement with material disposed on the cloth supporting surfaces 105.

With the device constructed as above described, its operation is as follows: The proper mold assemblies for the right and left lapels of 25 garments of one style are first inserted in the machine by inserting the flanges 143 and 144 of the molds under the plates 142 of the front and rear platforms. By this arrangement each mold 103 will be secured in elevated position as shown 30 in Fig. 10 and its cloth supporting piece 105 will drop down to rest on the supporting surface 101 of the table 100 with the corresponding edges of the piece 105 and ledge 110 closely abutting each other, being secured in that position by the 35 dowels 145 received by the corresponding recesses in the bottom of the piece 105.

The material is then inserted in pressing position and is molded and pressed in the manner described in my prior apparatus application. When 40 the presser member 150 is lowered to exert molding pressures on the material the faces 151 of the presser member will first engage the upper exposed surfaces of the molds 103 and depress them as is permitted by the spring pressed platforms 120, 121 and 122 which yieldingly hold the molds in elevated position. Further depression of the member 150 will cause initial contact between the faces 151 and the material and the continued downward movement of the member 50 150 will cause a lateral spreading of the material at its edge portions and a simultaneous further depression of the molds 103 until the final pressing closure is reached, in which position the machine is locked.

Fig. 13 indicates the machine locked closed in molding position and it will there be observed that the upper surface of the ledge 110 forms a continuation of the cloth supporting surface of the member 105 so that the material, represented 55 at 280, lies in a continuous flat plane from the edge 104 of the mold to the outer edge of the machine. The rib 180 is disposed in predetermined position relative to the molding edge 104 and it will be noted that when the machine is 60 closed the groove or recess 181 in the surface 151 of the member 105 will receive the protuberance in the material formed by the rib 180. I have found that the provision of such a complementary groove improves the formation of the fold 65 defining crease and at the same time insures that the material disposed on either side of the groove will be firmly engaged between the pressing surface 151 and the lower cloth supporting surface. By providing a permanent set of ribs 70 75

as a part of the ledges 110, I have eliminated the necessity for providing each cloth supporting piece with its individual rib as was contemplated by my prior construction. The variations in 5 distance from the rib 180 to the molding wall 104 as are required by changes in the style of the garment, can readily be provided for by constructing the different cloth supporting pieces 105 of the proper compensating widths.

10 I claim:

1. The method of shaping margins of material to be folded which comprises supporting the material, confining edge portions thereof to the desired contour by manipulating the material 15 to position its edge portions contiguous to an edge confining body, passing steam into the material to soften the same and subsequently pressing and molding the material by applying pressure to the surfaces of the material and resisting the lateral displacement of the edge portions 20 resulting from the pressure against the surfaces and simultaneously defining the position of a fold by impressing in the material an indentation to render the material easily foldable at a predetermined distance from its edge.
2. The method of shaping edge portions of material which comprises confining edge portions thereof to the desired contour by manipulating the material to position its edge portions contiguous to an edge confining body, passing steam 25 into the material to soften the same and subsequently pressing and molding the material by applying pressure to the surfaces of the material, resisting the lateral displacement of the edge portions 30 resulting from the pressure against the surfaces of the material and simultaneously passing the edge confining body transversely of the edge of the material.
3. The method of shaping the edge of garment 35 material which comprises confining edge portions of the material, extruding the edge of the material by applying pressure to the surfaces of the material and simultaneously resisting said extrusion and passing the confining body transversely of the edge of the material to iron the same.
4. The method of shaping the edge of garment 40 material which comprises confining edge portions of the material, passing steam through the material, drawing the edge of the material firmly 45 against its confining body, extruding the edge of the material by applying pressure to the surfaces of the material and simultaneously resisting said extrusion and passing the confining body transversely of the edge of the material to iron the same.
5. The method of shaping the points of a garment 50 which comprises placing the material adjacent an edge confining body, externally engaging the material and pressing the portion thereof to be pointed against the said edge confining body throughout substantially the entire edge portion to be molded whereby to compress the edge laterally to substantially the pointed 55 shape desired, and thereafter simultaneously applying pressure to the surface of the material to compress the material in the direction of the pressure thus applied, resisting lateral displacement of the edge portions initiated by said pressure and relatively moving the confining body 60 and material in a direction transverse of the edge of the material whereby to set the point in the shape desired.
6. The method of shaping the edge of garment 65 material which comprises placing edge portions of

the material adjacent an edge confining body, producing pressure against the edge of the material and relatively moving the confining body and the material in a direction transverse of the said edge of the material whereby to mold and iron the edge to the desired shape. 5

7. The method of shaping the edge of garment material which comprises placing edge portions of the material and an edge pressing body in abutting relationship, producing pressure between the edge of the material and the edge pressing body and relatively moving the pressing body and the material in a direction transverse of the said edge of the material, whereby to mold and iron the edge to the desired shape. 10

8. The method of shaping the edge of garment material which comprises placing edge portions of the material and an edge pressing body in abutting relationship, producing pressure between the edge of the material and the edge pressing body and moving the pressing body in a direction transverse of the said edge of the material, whereby to mold and iron the edge to the desired shape. 15

9. The method of shaping the edge of garment 25 material which comprises placing edge portions of the material adjacent an edge confining body, confining the surfaces of the material between substantially parallel pressure-applying surfaces, and thereafter applying pressure to the surfaces 30 of the material, producing pressure against the edge of the material and relatively moving the confining body and the material in a direction transverse of the said edge of the material.

10. The method of shaping the edge of garment 35 material which comprises confining and initially pressing the edge of the material to substantially the lateral shape desired and simultaneously producing undulations in the surface of the material adjacent the confined edge thereof, subsequently 40 increasing the pressure against the edge by applying pressure to the said undulations in the surface of the material and simultaneously relatively moving the confining body and the material in a direction transverse of the edge of the material 45 whereby to press the surface of the material and mold the edge thereof to the desired shape.

11. The method of shaping the edge of garment material which comprises placing the material adjacent an edge confining body, steaming the 50 material to render it plastic, externally engaging the material and pressing plastic edge portions thereof against the said edge confining body and simultaneously producing undulations in the surface of the material adjacent the 55 confined edge thereof, subsequently producing pressure between the edge and its confining body by applying pressure to the said undulations in the surface of the material and simultaneously relatively moving the confining body 60 and the material in a direction transverse of the edge of the material whereby to press the surface of the material and mold the edge thereof to the desired shape.

12. The method of shaping margins of material 65 to be folded which comprises confining and initially pressing the edge of the material to substantially the lateral shape desired and simultaneously producing undulations in a surface of the material adjacent the confined edge thereof, 70 engaging and lightly depressing an elongated portion of one surface of the material disposed in predetermined position relative to the confined edge thereof and thereafter simultaneously increasing the pressure against the edge and fixing 75

an elongated impression in the material by applying pressure against the undulated surface thereof and relatively moving the confining body and the material in a direction transverse of the edge of the material whereby to mold the edge of the material to the shape desired and render the material easily foldable at a predetermined distance from its molded edge.

13. The method of shaping margins of material to be folded which comprises placing the material adjacent an edge confining body, steaming the material to render it plastic, externally engaging the material and pressing plastic edge portions thereof against the said edge confining body and thereafter simultaneously applying increased pressure between the edge and its confining body and depressing an elongated portion of a surface of the material in predetermined position relative to the edge confining body by applying pressure against a surface thereof and relatively moving the confining body and the material in a direction transverse of the edge of the material whereby to mold the edge of the material to the shape desired and render the material easily foldable at said depressed portion.

14. The method of shaping the lapel portions of a garment which comprises steaming the material to render it plastic, engaging the tip of the lapel adjacent the extremity thereof and drawing it firmly into an edge molding recess whereby to compress the edge of the lapel tip to substantially the lateral shape desired, fastening the lapel tip in its laterally compressed position and subsequently producing pressure between the edge of the lapel tip and its molding recess by applying pressure to the surface of the material whereby to press the surface of the lapel tip and mold the edge thereof to the shape desired.

15. The method of shaping the lapel portions of a garment which comprises steaming the material to render it plastic, manipulating the tip of the lapel to press plastic edge portions thereof against an edge molding wall, manipulating edge portions of the collar and edge portions of the lapel remote from the tip to distribute and press the same against an edge molding wall and simultaneously delineating the shape of the notch separating the lapel and collar and subsequently producing pressure between the edge of the material and its molding wall and moving the edge confining body and the material relatively in a direction transverse of the edge of the material to mold the edge of the material to the shape desired.

16. The method of shaping the lapel portions of a garment which comprises steaming the material to render it plastic, manipulating the tip of the lapel to press plastic edge portions thereof against an edge molding wall, manipulating edge portions of the collar and edge portions of the lapel remote from the tip to distribute and press the same against an edge molding wall and simultaneously delineating the shape of the notch separating the lapel and collar and subsequently producing pressure between the edge of the material and its molding wall to mold the edge of the material to the shape desired and forming an impression in the surface of the material in predetermined position relative to the shaped edge thereof to render the material easily foldable.

17. In a pressing machine adapted for use with a pressing mold comprising a cloth supporting member and an edge molding wall, the combination of a table adapted to support the cloth supporting member, means for removably securing

the cloth supporting member on the table, means for yieldingly supporting the edge molding wall to expose a molding surface of a height which exceeds the thickness of the material to be pressed and pressing means adapted to depress the molding wall and to press the material.

18. In a pressing machine adapted for use with a pressing mold comprising a cloth supporting member and an edge molding wall, the combination of a table adapted to support the cloth supporting member, means for removably positioning and securing the cloth supporting member on the table, said means including a ledge on the periphery of the table adapted to abut the said member, means for yieldingly supporting the edge molding wall with an exposed molding surface of a height to exceed the thickness of the material to be pressed and a presser member adapted to depress the molding wall so that its height does not exceed substantially the thickness of the material whereby to press the surface of the material and simultaneously to mold the edge thereof.

19. In a pressing machine adapted for use with a pressing mold comprising a cloth supporting member and an edge molding wall, the combination of a table adapted to support the cloth supporting member, means for removably positioning and securing the cloth supporting member on the table, said means including a ledge on the periphery of the table adapted to abut the said member and having an exposed surface forming a continuation of the supporting surface of said member, means for yieldingly supporting the edge molding wall with an exposed molding surface of a height to exceed the thickness of the material to be pressed and a presser member adapted to depress the molding wall so that its height does not exceed substantially the thickness of the material whereby to press the surface of the material and simultaneously to mold the edge thereof.

20. In a pressing machine adapted for use with a pressing mold comprising a cloth supporting member and an edge molding wall, the combination of a table adapted to support the cloth supporting member, means for removably positioning and securing the cloth supporting member on the table, said means including a ledge on the periphery of the table adapted to abut the said member and having an exposed surface forming a continuation of the supporting surface of said member, a rib on the ledge adapted to impress the material with an elongated indentation whereby to initiate a fold in a predetermined portion of the material, means for yieldingly supporting the edge molding wall with an exposed molding surface of a height to exceed the thickness of the material to be pressed and a presser member adapted to depress the molding wall so that its height does not exceed substantially the thickness of the material whereby simultaneously to press the surface of the material, mold the edge thereof and initiate the fold in a predetermined portion of the material relative to the molded edge.

21. In a pressing machine adapted for use with a pressing mold comprising a cloth supporting member and an edge molding wall, the combination of a table adapted to support the cloth supporting member, means for removably positioning and securing the cloth supporting member on the table including a ledge on the periphery of the table adapted to abut the said member and having an exposed surface forming a continuation of the supporting surface of said member, a rib on the ledge adapted to impress the material with

- an elongated indentation whereby to initiate a fold in a predetermined portion of the material, means for yieldingly supporting the edge molding wall with an exposed molding surface of a height to exceed the thickness of the material to be pressed, a presser member adapted to depress the molding wall so that its height does not exceed substantially the thickness of the material whereby to press the surface of the material and simultaneously to mold the edge thereof, and a recess in the surface of the presser member adapted to receive protruding portions of the material adjacent the rib.
22. In a pressing machine adapted for use with a pressing mold comprising a cloth supporting member and an edge molding wall, the combination of a table adapted to support the cloth supporting member, means for removably positioning and securing the cloth supporting member on the table including a ledge on the periphery of
